Primary Examiner — Catherine A Tuttle(74) *Attorney, Agent, or Firm* — Simpson & Simpson, PLLC; Michael Nicholas Vranjes(57) **CLAIM**

The ornamental design for an aerosol canister case with indication ring, as shown and described.

DESCRIPTION

FIG. 1 is a front top perspective view of the aerosol canister case with indication ring showing my new design;

FIG. 2 is a rear bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depicting the connection means are for illustrative purposes only; and form no part of the claimed design.
